UNITED STATES PATENT OFFICE.

ABRAHAM HORNUNG, OF CZARNA, NEAR PILZNO, AND ISIDOR SPERLING, OF TARNOPOL,
AUSTRIA-HUNGARY.

ELECTRIC BELT.

No. 910,474

Specification of Letters Patent.

Patented Jan. 19, 1909.

Application filed July 12, 1907. Serial No. 383,405.

To all whom it may concern:

Be it known that we, ABRAHAM HORNUNG, merchant, residing at Czarna, near Pilzno, Galicia, and ISIDOR SPERLING, merchant, residing at 12 Breitegasse, Tarnopol, Galicia, Austria-Hungary, both subjects of the Emperor of Austria-Hungary, have invented new and useful Improvements in Electric Belts or Bands, of which the following is a specification.

The object of this invention is to provide convenient and satisfactory means for sending a current of electricity through some part of a person, on the occurrence of a given movement or event. It may also serve as a silent time-alarm.

To this end the said invention consists in the construction and combination of parts hereinafter more particularly set forth and claimed.

The accompanying drawing represents a perspective view of apparatus embodying our invention, applied to a person's wrist or forearm.

On a band 1 or a similar article or part metal contact plates 2 are fastened and are connected by wires 3 with a source of current 4, the most advantageous form of which is a dry battery. The power of the current from this battery can be altered by means of an inductor 5. A clock 6 is switched into this circuit and is arranged in the ordinary way so that it will close the circuit at a certain fixed moment. It is a good plan to have

the head of the clock made as an incandescent lamp, so that it will be easier for the person to find the switch for the throwing off the current after he has been awakened.

The band 1 as shown in the figure is fixed round the forearm, but it may be fixed on any other part and it should be noted that the battery and the clock can easily be car-

ried in the pocket. The mode of attachment shown in the drawing is particularly suitable for travelers by railway and in such cases the battery and the clock can be carried in the vest pockets and the wires passed through the armholes. It will of course be understood that the strength of current, that the person using the appliance can stand, must previously be ascertained and the inductor set accordingly.

Having now particularly described and ascertained the nature of our said invention and in what manner the same is to be performed and what we desire to secure by Letters-Patent is:

1. A band adapted to be fastened about the wrist or other part of a person and provided with contacts arranged at intervals to send an electric current through the flesh, in combination with a source of electricity, circuit conductors and a watch switched into the circuit and arranged to close the same when the hands indicate a certain time on the dial.

2. A band adapted to be fastened on a person and provided with contacts arranged to send an electric current through the flesh, in combination with a generator and conductors of said current, a time piece switched into the circuit to close the same when the hands point to a certain time and an electric lamp attached to said time piece, arranged in said circuit and serving as an additional indication or alarm.

In testimony whereof we affix our signatures in presence of two witnesses.

ABRAHAM HORNUNG.
ISIDOR SPERLING.
